UNITED STATES PATENT OFFICE.

HERBERT ARTHUR SMITH, OF ST. PAUL, MINNESOTA.

CHECK-BOOK COVER.

1,217,849.

Specification of Letters Patent. Patented Feb. 27, 1917.

Application filed October 11, 1916. Serial No. 125,091.

To all whom it may concern:

Be it known that I, HERBERT ARTHUR SMITH, a citizen of the United States, residing at St. Paul, in the county of Ramsey 5 and State of Minnesota, have invented a new and useful Check-Book Cover, of which the following is a specification.

This invention aims to provide novel means whereby checks or slips of any other kind will be prevented from being flattened down in a pocket check book, thereby avoiding a creasing of the checks transversely, it being a matter of common knowledge that if a check is creased down too tightly transversely, it can be written upon only with difficulty, when opened out flat.

With the above and other objects in view which will appear as the description proceeds, the invention resides in the combination and arrangement of parts and in the details of construction hereinafter described and claimed, it being understood that changes in the precise embodiment of the invention herein disclosed can be made within 10 the scope of what is claimed, without departing from the spirit of the invention.

In the accompanying drawings:—

Figure 1 shows in side elevation, a check book embodying the present invention;

Fig. 2 is a top plan wherein the check book has been opened, parts being broken away; and

Fig. 3 is a perspective view showing the shaper over which the checks are folded.

The structure forming the subject matter of this application may be assembled with check books of different kinds, but in the present instance there is shown a check book comprising a back 1 provided on one end 35 with an extension 2 which may have an exterior pocket 3. The other end of the back 1 is provided with an outer cover 4 terminating in a tongue 5. Checks or slips of any other kind, indicated at 7, are connected at 40 one end, as shown at 8, in any suitable manner, with the back 1, near to the point where the back 1 joins the extension 2.

In the ordinary operation of a book of the kind hereinbefore set forth, the extension 2 is folded forwardly until it rests on the checks or slips 7 near to their stub ends. The checks 7 then are folded backwardly on top of the extension 2. The cover 4 is folded backwardly, on top of the ends of the checks.

The tongue 5 on the end of the cover 4 is extended beneath the back 1, as indicated in Fig. 1, and is held in place on the back by means of the snap fastener 6.

The disadvantage attendant upon such a procedure is that the checks or slips 7 are folded too sharply across the forward edge of the extension 2. As a consequence, the checks or slips are creased, and can be written upon only with difficulty.

In order to prevent the checks from being folded too sharply, as above mentioned, recourse is had to the structure depicted in Fig. 3 of the drawings, which shows in perspective, a shaper, adapted to be assembled with the free end of the back 1. This shaper 70 comprises a plate 9, the side edges of which are bent to form overhanging flanges 10. The transverse forward edge of the plate 9 is fashioned into a circular bead 11, the longitudinal edge of which is free, as indicated 75 at 12. The bead 11 preferably has some resiliency.

In practical operation, the free end of the extension 2 is inserted beneath the flanges 10, and then the checks or slips 7 are folded 80 across the enlarged bead 11, after the manner of Fig. 1, it being obvious that, under such circumstances, a sharp creasing or folding of the checks or slips will be avoided. The bead has some resiliency, since one of 85 its edges is free as shown at 12 and this construction enables the tongue 5 to be drawn into place beneath the back 1, and to be engaged by the snap fastener 6 as shown in Fig. 1. Further, since the bead 11 has some 90 resiliency, the bent checks will be held tightly in place, even though some of the checks may have been torn out.

Having thus described the invention, what is claimed is:—

1. A check book embodying a back; an extension connected with one end of the back; an outer cover connected with the other end of the back; checks connected with the back, the extension being adapted to be folded over on top of the checks, the checks at their free ends being adapted to be folded over on top of the extension, and the outer cover being adapted to be folded over onto the folded ends of the checks; and a shaper carried by the free end of the extension and of greater diameter than the thickness of the extension, the shaper being curved and en-

gaging the checks, to prevent a sharp creasing thereof, when the checks are folded across the shaper.

2. A check book embodying a back; an extension hinged to one end of the back; checks connected with the back, the extension being adapted to be folded over on top of the checks, and the checks being adapted to be folded back on top of the extension; and a shaper comprising means for receiving

the free end of the extension removably, the shaper including a curved head across which the checks are adapted to be flexed.

In testimony that I claim the foregoing as my own, I have hereto affixed my signature 15 in the presence of two witnesses.

HERBERT ARTHUR SMITH.
